UNITED STATES PATENT OFFICE.

JULÉS RENE BLUM, OF PARIS, FRANCE, ASSIGNOR TO COMPANY "L'ASPIRATOR," OF PARIS, FRANCE, A CORPORATION OF FRANCE.

FILTERING DEVICE FOR DUST-REMOVING PNEUMATIC MACHINES.

No. 853,914.

Specification of Letters Patent.

Patented May 14, 1907.

Original application filed April 19, 1906, Serial No. 312,672. Divided and this application filed February 20, 1907, Serial No. 358,451.

To all whom it may concern:

Be it known that I, JULÉS RENÉ BLUM, civil engineer, a citizen of France, residing at 49 Boulevard Péreire, Paris, France, have invented new and useful Improvements in Filtering Devices for Dust-Removing Pneumatic Machines, of which the following is a specification.

This invention which is a division of the application Serial No. 312,672 filed April 19, 1906, relates to an improved filtering device adapted to be used in connection with machines for removing dust by suction from carpets, furniture, curtains, tapestry and the like, and the principal object of the invention is to provide for a filtering device in which the filtering material may be easily cleaned.

The accompanying drawing shows a vertical sectional view of a dust removing pneumatic machine incorporating the improved filtering device.

The dust removing machine comprises the usual flexible aspiration tube *o* terminated in a metallic suction mouth *o'*, the filtering devices which will be hereinafter described and claimed, and the bellows 1, 2, 3, 4 of the kind described and claimed in a separate application filed this day.

The filtering devices are inclosed in a hermetically closed box *D* of sheet metal arranged upon the stationary flap of the upper bellows 1. This box is provided with a tight closing door *d* and with two ajutages *e* *f* which are adapted to be fitted respectively in the aspiration tube *o* and in another ajutage *g* leading to the suction compartment *k* of the machine. Within the box *D* is arranged an ovoid receptacle *A* the walls of which consist of a frame of metallic hoops inclosed in an envelop or shell *B* of loose fibrous material or the like. This envelop is adapted to retain the dust and to let pass therethrough only the air.

The communication between the interior of the filtering envelop *B* and the suction compartment *k* is insured by means of sleeve or ring *m* provided for at the end of the ovoid frame *A* and adapted to be snugly fitted over the ajutage *f* of the box *D*, the free border of the envelop *B* being attached in any convenient manner to said sleeve or ring *m*.

During the operation, the dust-laden air

drawn in through the flexible tube *o*, being compelled to pass through the filtering envelop *B* before reaching the bellows, deposes its dust on the fibrous material of the envelop and within the box *D*. The air enters thus the receptacle *A* and the bellows perfectly pure.

For removing the envelop *B* in order to clean it, one proceeds in the following manner: The lid *n* of the casing of the machine is first opened, the tube *o* is drawn out of the ajutage *e*, the box *D* is then slightly moved toward the left to detach the ajutage *f* of the box from the ajutage *g* leading to the suction compartment *k*. The whole box *D* is then drawn out, its door *d* is opened and finally the receptacle *A* with the envelop *B* is drawn out of the box, which allows thus to remove the envelop *B*.

To replace the filtering devices in the proper position, one proceeds in a reverse manner to the one above described.

Having now described my invention, what I claim as new and desire to secure by Letters Patent is:

In a machine for removing dust by suction from carpets, furniture, curtains, tapestry and the like, a filtering device comprising in combination, a hermetically closed box *D* adapted to rest upon the stationary flap of the upper bellows of the machine, a door *d* fitted in said box, an ajutage *e* provided for in said box and adapted to be fitted in the aspiration tube *o* of the machine, a second ajutage *f* provided for in said box and adapted to be fitted in an ajutage *g* leading to the suction compartment, an ovoid receptacle *A* having its walls made of metallic hoops, a sleeve or ring *m* provided for at one end of the receptacle and adapted to be fitted over the second ajutage *f* of the box *D*, and an envelop or shell *B* of loose fibrous material arranged about the ovoid receptacle, substantially as described and for the purpose set forth.

In testimony whereof I have signed my name to this specification in the presence of two subscribing witnesses.

JULES RENÉ BLUM.
